COOKY JAR

Jess L. Parentice, Zanesville, Ohio, assignor to Shawnee Pottery Company, Zanesville, Ohio, a corporation of Ohio

Application March 18, 1948, Serial No. 145,191

Term of patent 3½ years

(Cl. D44—15)

To all whom it may concern:

Be it known that I, Jess L. Parentice, a citizen of the United States of America, residing at Zanesville, in the county of Muskingum and State of Ohio, have invented a new, original, and ornamental Design for Cooky Jar, of which the following is a specification, reference being had to the accompanying drawings, forming a part thereof, wherein:

Fig. 1 is a side elevational view of a cooky jar, showing my new design;

Figs. 2 and 3 are other side elevational views of the jar rotated 60 and 120 degrees, respectively, from the position of Fig. 1;

Fig. 4 is a top plan view; and

Fig. 5 is a bottom plan view thereof.

I claim:

The ornamental design for a cooky jar, as shown.

JESS L. PARENTICE.
